METHOD OF TREATING USED-BURLAP BAGS

Filed April 14, 1930

FIG. 1.

FIG. 2.

FIG. 3.

Inventor:
George I. Goldwyn,
By: Arthur W. Nelson

Atty.

UNITED STATES PATENT OFFICE

GEORGE I. GOLDWYN, OF CHICAGO, ILLINOIS

METHOD OF TREATING USED BURLAP BAGS

Application filed April 14, 1930. Serial No. 443,940.

This invention relates to an improved method of treating used burlap bags and it consists of the matter hereinafter described and more particularly pointed out in the appended claim.

The primary object of the invention is to provide an improved method by means of which the seam of a used burlap bag, may be made stronger than it originally was and much neater in appearance because of the absence of frayings and ravelings.

The above mentioned object of the invention as well as others together with the many advantages thereof will more fully appear as I proceed with my specification.

In the drawings:—

Fig. 1 is a perspective view of a used burlap bag after the seam thereof has been treated in accordance with my invention.

Fig. 2 is a perspective view through the seam of a used burlap bag after it has been turned inside out and has been treated in accordance with one step of my invention.

Fig. 3 is a view similar to Fig. 2 after the seam has been treated in accordance with another step of my invention.

In that industry wherein used burlap bags are reconditioned for reuse, one of the main difficulties met with is the treating of the seam. Such bags when presented to the trade after cleaning and renovating, are turned inside out to obliterate the usual brands and trade marks printed upon the bags. When thus turned inside out the folded over and stitched together margins of the bag fabric from which the seam is made are exposed and the edges thereof are always more or less frayed and raveled and present an undesirable appearance.

Again with these margins on the outside of the turned bag, the frayed edges slough off in use and soon approach the original stitching holding them together with the result that the seam as a whole weakens and opens up so that the bag soon becomes unfit for further service.

In the original making of a burlap bag 1, a piece of burlap of the desired area is folded over upon itself to bring its edges in registration to provide the two walls 2 and 3

of the bag each with a turned over margin 2^a and 3^a respectively and a line of stitching 4 is then run along one side and end of the folded over bag material. Thereafter the thus far finished bag is turned inside out to 55 provide a finished bag ready for the trade as a plain unprinted bag.

After the bag has been in use, and its contents have been removed, it is generally considered as waste by the original purchaser. 60 To recondition the bag, for reuse certain establishments clean and mend the bags. As the bags cannot go back to the purchasing public with the original brands and trade marks on the outside, they are again turned inside out. This, however, leaves the frayed edges 2^b and 3^b of the margins 2^a and 3^a of the bag, extending toward the opposite side of the bag and beyond the now exposed line of stitching 4 so that the bag is indeed weakened and does not have the neat appearance which so appeals to the purchaser.

In accordance with my invention, I run a line of overcast stitching 5 through said folded over margins and the bag wall portions 75 engaged thereby. In running in this line of stitching, the interlooping portions 5^a thereof are spaced well within the frayed edges 2^b and 3^b and the loops 5^b thereof pass around the folded edges of the seam and cross the 80 original line of stitching.

Thereafter by suitable mechanism, I trim off the frayed edges 2^b and 3^b adjacent but beyond the interlooped portions 5^a of the overcast stitching as shown in Fig. 3 and this 85 leaves the bag with a clean cut appearing seam bound by the loops 5^b of the overcast stitching and with the original line of stitching 4 covered and protected thereby.

Thus the seam of the bag is made much 90 stronger and has that appearance which readily enhances its salability.

While in describing my invention, I have referred in detail to the arrangement of the parts of the bag, as well as to the manner in 95 which they are operated upon, the same is to be considered merely as illustrative so that I do not wish to be limited thereto except as may be specifically set forth in the appended claim.

I claim as my invention:—

The method of treating used bags of burlap and the like which consists in turning the bag inside out, thereby exposing margin portions 5 above and below the body fabric layers of the bag, the frayed edges of said margin portions extending inwardly and also exposing the line of stitching which passes through the two margin portions and the two body layers to 10 secure them together, in forming a line of overcast stitching with the interconnecting loops thereof passing through both margin portions and both layers of the bag fabric in a plane between the first mentioned line of 15 stitching and said frayed edges and with the other loops of the overcast stitching passing around the folds of said margin and body fabric and crossing the first mentioned line of stitching and, subsequent to turning the 20 bag inside out, removing the frayed edges of the margins.

In testimony whereof, I have hereunto set my hand, this 9th day of April, 1930.

GEORGE I. GOLDWYN.
